UNITED STATES PATENT OFFICE.

LEWIS CLYDE SHARPE, OF KERRVILLE, TEXAS.

VALVE-STEM WASHER.

Application filed November 8, 1922. Serial No. 599,686.

To all whom it may concern:

Be it known that I, LEWIS CLYDE SHARPE, a citizen of the United States, residing at Kerrville, in the county of Kerr and State 5 of Texas, have invented certain new and useful Improvements in Valve-Stem Washers, of which the following is a specification.

This invention relates to an improved means for sealing the opening in the de-10 mountable rim or wheel rim about the valve stem, whereby to prevent the entrance of water or the like between the rim and casing and between the casing and tube, to thereby prevent the corrosion of the rim and 15 the resultant rust attack on the tube and casing.

In the ordinary application of a pneumatic tire to a demountable rim or directly to the wheel rim, the opening through which 20 the valve stem projects is necessarily of greater diameter than that of the valve stem. This provides an opening through which water, snow, dirt, and the like, may find its way between the casing and rim and 25 to some extent between the tube and casing. The corrosion of the rim which necessarily follows the entrance of water or the like would eventually weaken both tube and casing, and thereby materially shorten the life 30 of these parts.

The present invention is directed to a washer of more or less particular form which may be inserted over the valve stem within and between the edges of the casing, 35 this washer being of a compressible material and acting under the internal pressure of the tube to absolutely seal the opening in the demountable rim or wheel rim and also substantially fill the space about the valve 40 stem between the tube and casing. Thus, the entrance of water or the like is absolutely prevented and the damage naturally resultant to the tube and casing from such water entrance is entirely obviated.

45 The invention is illustrated in the accompanying drawings, in which:

Fig. 1 is a view in transverse section through an inflated pneumatic tire.

50 Fig. 2 is a longitudinal section of the same.

Fig. 3 is a perspective view of the washer.

The improved washer, which may be and preferably is, constructed of rubber, comprises a body 1 of substantially conical 55 form, having a comparatively broad base 2

and a central opening 3. The opening 3 is circumferentially enlarged at 4 adjacent the base, and the outer wall of the body merges into the wall of the opening 3 at the reduced or smaller end of the body to present 60 at this end a comparatively narrow edge 5.

The washer as a separate and a wholly independent element, is applied over the valve stem 6, the enlarged portion 4 of the opening 3 receiving the outer securing bridge 65 washer 7 of the valve stem, and the base 2 of the washer bearing more or less snugly against the inner tube 8 around said bridge washer. The opening 3 is of a size to snugly embrace the valve stem proper and 70 the conical formation of the washer body provides for more or less filling of the space between the bead portions 9 of the casing 10.

It will be apparent that a washer thus occupies a space between the inner tube and 75 casing with the reduced or knife edge projecting into the space between the inner edges of the casing beads. Under the internal pressure of the tube, this washer will be compressed and the knife edge 5 forced into 80 the opening 11 provided in the rim 12 for the passage of the valve stem 6 there-through. Thus, this opening will be completely sealed and it will be impossible for water, dirt, snow, or the like, to enter. The 85 inner surface of the rim, the marginal edge of the casing, and the surface of the inner tube, which would be otherwise reached by this water or dirt, are thus absolutely protected, and the life of these parts materially 90 increased.

As the opening 11 provides practically the only possible entrance for dirt and water in the use of the tire, the sealing of this opening will prevent rusting of the rim and a 95 consequent deterioration of the casing and tube.

The washer is a wholly independent and separable element, may be readily and conveniently applied to any tire at any time, 100 and if worn or deteriorated under constant use, may be readily and cheaply renewed.

While the invention is here shown and described as a washer per se, it is to be understood that the invention substantially 105 comprehends a separable means to be applied to the valve tube to seal the opening in the demountable or wheel rim through which said tube passes, it being understood that the washer is equally effective with 110

2
tires applied directly to the wheel rim as with tires of the type applied to demountable rims.

Claim:

- In combination a wheel rim, a pneumatic tire mounted on the rim, including a tube, a valve stem extending from the tube and through the rim, and a bridge washer having inclined end portions at all times free
10 of contact with the rim, of a resilient washer having a central opening through which the valve stem passes, said resilient washer being formed with a broad surface which engages the bridge washer when acted
15 upon by the tube when under pneumatic

pressure, the washer having a conical outer surface confined and guided by the bridge washer and the inner surfaces of the bead of the pneumatic tire, said washer having a reduced edge at its smaller end adjacent the 20 opening therein, whereby when pressure is introduced in the tube the inclined end portions of the bridge washer and the inclined surfaces of beads of the tire force the reduced edge of the resilient washer into the 25 opening in the rim around the valve stem and forms a seal.

In testimony whereof I affix my signature.

LEWIS CLYDE SHARPE. [L. S.]
